UNITED STATES PATENT OFFICE.

JOHN DICKSON, OF VANCOUVER, WASHINGTON.

BOX-CAR LINING.

1,262,025.

Specification of Letters Patent. Patented Apr. 9, 1918.

Application filed July 28, 1917. Serial No. 183,342.

To all whom it may concern:

Be it known that I, JOHN DICKSON, a citizen of the United States, and a resident of Vancouver, in the county of Clarke and

5 State of Washington, have invented an Improvement in Box-Car Linings, of which the following is a specification.

My invention relates to improvements in linings for box cars, house cars, etc., and it 10 consists in the combinations, constructions and arrangements herein described and claimed.

An object of my invention is to provide a removable lining which may be used when 15 comminuted material, such as coal, grain, and the like, is shipped.

A further object of my invention is to provide a lining which will protect the sides of the car and which will also prevent loss 20 of the comminuted material.

A further object of my invention is to provide a lining which may be readily removed or replaced with a minimum of labor.

Other objects and advantages will appear 25 in the following specification, and the novel features of the invention will be particularly pointed out in the appended claims.

My invention is illustrated in the accompanying drawing, forming a part of this application, in which—

Figure 1 is a sectional view through a car provided with my improved lining.

Fig. 2 is a sectional view through one of the doors of the car and through the 35 delivery tube adjacent thereto.

Fig. 3 is a perspective view of the delivery tube and a portion of the lining.

Fig. 4 is a horizontal section through the car and lining.

40 Fig. 5 is a vertical section at right angles to Fig. 1.

In carrying out my invention I make use of a car of the ordinary type, such a car being shown at A in the drawings. On the 45 interior of the car, next to the side walls thereof, I secure a sack B, this sack being made preferably of canvas or other similar material. The sack is provided with a series of eyes C which are arranged to fit 50 over hooks D in the sides of the car near the top thereof.

Slidable doors E are preferably disposed at each end of the car and at the sides thereof, and at each of these slidable doors is a 55 delivery or discharge tube T which is made

of canvas and which being flexible may be folded, when not in use, and retained behind the door, in the manner shown in Fig. 2.

From the foregoing description of the various parts of the device the operation there- 60 of may be readily understood.

The car is filled with the comminuted material such as that shown at F in Fig. 1, and the delivery tubes T are folded behind the doors E, see Fig. 2. In this condition the 65 material is shipped, and when it is desired to empty the car the doors E are opened, the tubes T are unfolded, and the material is allowed to run out by gravity into suitable receptacles.

This device may be used for all kinds of comminuted material such as grain, pulverized fuel, or other pulverized material. The sacks protect the sides of the car and there is practically no loss of the material.

It is but a few moments' work to take out the lining by removing the eyes C from the hooks D, when the car may be used for other purposes.

It will be understood that after as much 80 material has run out as will come by gravity, the sack is manipulated by hand so as to direct the balance of the material toward the tube which is open at the place where delivery is to be made.

85 I claim:

1. The combination with a box car having a series of hooks on its side walls, of a sack made of fabric and conforming to the interior of the car, said sack being provided 90 with a series of eyes arranged to engage the hooks for supporting the sack in position, and flexible delivery tubes leading from said sack.

2. The combination with a box car having 95 a series of hooks on its side walls, of a sack made of fabric and conforming to the interior of the car, said sack being provided with a series of eyes arranged to engage the hooks for supporting the sack in position, 100 and flexible delivery tubes leading from said sack, said flexible delivery tubes being capable of being folded, said car having a slide- able door arranged to retain the folded tube in position when the door is shut.

JOHN DICKSON.
